(57) **CLAIM**

The ornamental design for a dispenser bag, as shown and described.

DESCRIPTION

FIG. 1 is an isometric view of the dispenser bag as it would appear filled with a liquid or viscous material such as, for example, a condiment; and,

FIG. 2 is a front view of the dispenser bag as it would appear filled.

Sides of the invention not shown are disclaimed.

1 Claim, 2 Drawing Sheets

FIG. 1

FIG. 2
